AUTOMATIC GRINDING MACHINE

Harry Arter, Worcester, Mass., assignor to Arter
Grinding Machine Company, Worcester, Mass.,
a corporation of Massachusetts

Application March 13, 1936, Serial No. 68,635

10 Claims. (Cl. 51—95)

This invention relates to automatic grinding machines and other machine tools. It will be herein disclosed as embodied in a grinding machine of the general type shown and described in

5 United States Letters Patent No. 1,736,967.
In machines of this general character, automatic mechanism is provided for producing relative approaching and receding movements of the work and grinding wheel, or other tool, during 10 each cycle of operations of the machine. Usually this operation is accomplished by means of a power driven cam and suitable connections through which said cam is enabled to move the tool toward and from the work, it ordinarily being 15 more convenient to move the tool than the work. In a typical construction the operating mechanism is so organized and arranged as to produce a rapid approach of the tool to the working zone, then a relatively slow approach in the working 20 zone which brings the tool in contact with the work and feeds it at a predetermined rate, next a dwell during which the tool finishes its operation and sizes the work to the desired dimensions, and finally a quick receding movement of 25 the tool. In prior machines it has been customary to transmit mechanically the motion imparted by some power driven element, such as a cam, to the tool head, and the matter of arranging and positioning the various elements of the 30 transmitting mechanism relatively to the other parts of the machine frequently is extremely troublesome and inconvenient and imposes undesirable limitations upon the design. Furthermore, such a transmitting mechanism does not 35 permit of any large degree of flexibility, either as to the location of the parts, or to the desirable modification of the movements transmitted to them or by them. In addition, these mechanisms are expensive to manufacture, and the degree of 40 accuracy with which they will operate is affected greatly by the nature of the design and consequently, by those limitations which the design has been compelled to meet.

The present invention deals especially with 45 these considerations. It aims to devise a power transmitting mechanism for use in such relationships as those above described, which will have the desirable features of convenient adaptability to different designs, simplicity in construction, 50 flexibility, accuracy in operation, and economy in construction costs. The invention involves both a new method and also a novel machine organization.

The nature of the invention will be readily 55 understood from the following description when

read in connection with the accompanying drawings, and the novel features will be particularly pointed out in the appended claims.

In the drawings,

Figure 1 is a vertical, sectional view, somewhat 5 diagrammatic in character, of an automatic grinding machine organized in accordance with this invention;

Fig. 2 is a development of a typical cam used in the construction shown in Fig. 1; 10

Fig. 3 is a diagrammatic view of said cam;

Fig. 4 is a diagrammatic view of an hydraulic system showing the provision for self-replenishment of the liquid column utilized for power transmitting purposes which forms an important 15 feature of this invention;

Fig. 5 is a view similar to Fig. 4 illustrating another hydraulic system embodying features of the invention;

Fig. 6 is a diagrammatic view illustrating still 20 another modification;

Figs. 7 and 8 are plan and development views, respectively, of a cam used in the system shown in Fig. 6;

Figs. 9 and 10 are corresponding views of 25 another cam; and

Fig. 11 is a view similar to Fig. 1 showing another modification.

Referring first to Fig. 1, the machine there shown comprises a frame 1 on which is mounted 30 a bed piece 2 connected with the frame by a pivot 2' about which the bed may be angularly adjusted relatively to the frame. A wheel head 3 is mounted in guideways provided in the bed 2 for sliding movement toward and from the work 35 supporting mechanism, indicated diagrammatically at 6. Adjustment of the wheel head and the parts carried thereby relatively to the work may be made through operation of the hand wheel 7. The grinding wheel 5 is secured rigidly 40 to a shaft 4 which is mounted on a quill 46, the quill being supported for limited rotative movement about its own center O, while the shaft 4 is eccentrically disposed with reference to said center. The arrangement is such that rotation 45 of the quill in a counterclockwise direction will move the shaft 4 and the wheel 5 away from the work while a rotative movement of the quill in the opposite direction will have a reverse effect. It will be observed that the mounting of the 50 wheel, the wheel head and the bed are such that compensation for wear of the grinding wheel may easily be made through adjustment of the hand wheel 7. Suitable adjustments for the taper of the work can also readily be produced, while the 55

relative approaching and receding movements of the work and wheel produced through the movement of the quill 46 are independent of, and unaffected by, the adjustments just described.

5 All of these parts may be constructed, arranged and operated in the manner disclosed in the patent above referred to, and reference may be made thereto for a more complete disclosure of the construction and operation of the various 10 units of the machine, and more especially of a typical mechanism for operating the quill similar to that illustrated at 46.

In the machine disclosed in the patent above referred to, the operation of the quill is produced solely by mechanical means. With a view to avoiding the limitations which the use of such a mechanism necessarily involves, the present invention proposes to replace the mechanism for transmitting the movement of the power operated cam to the quill with a column of fluid so arranged that the motion of the cam will be faithfully and accurately transmitted to the quill.

It is recognized that in any fluid pressure system 25 leakage is unavoidable, and that the effect of leakage occurring in successive cycles of operation of a machine of the type here shown, would seriously impair the accuracy of such operations. Accordingly, another important object of this 30 invention is to compensate for such leakage at intervals so frequent that any cumulative effect will be avoided and the system will be maintained continuously in such condition that it will function faithfully and accurately.

35 Referring again to Fig. 1, the cam shaft which controls the time relation of the functions of the machine is illustrated at 24. It carries a cam 25, the operating surface of which is divided into four sections, as illustrated more 40 clearly in Figs. 2 and 3, which control the movements of the wheel toward and from the work and divide said movements into substantially the four periods above referred to. The slopes C—D of the cam produce the quick movement of the 45 wheel away from the work; the lobe D—A holds the wheel stationary but away from the work; the slope A—B permits the rapid approach of the wheel toward the work, and the section B—C permits a controlled approach of the wheel in 50 the working zone, this section being functionally divided, as hereinafter described, into approach and dwell periods. The foregoing constitutes a complete cycle of the cam.

As shown in Fig. 1, the cam 25 operates a bell 55 crank lever 26 which is connected through a link to the piston rod 27 of a piston 28 working in a cylinder 35 which is attached to the machine at any convenient point. Starting at the point C on the cam, it first moves the lever in such a direction as to tend to compress the liquid in the cylinder, and this motion is transmitted through the liquid column in the pipe 29, which connects the cylinder 35 with another cylinder 36 mounted 60 within the wheel head. The movement of the piston 28 thus is transmitted to and produces a corresponding movement of the piston 30 in the latter cylinder. Projecting from the piston 30 is a piston rod 31 bearing against an arm 32, so that the upward movement of the piston produces a counter-clockwise rotation of the quill 46 and therefore moves the wheel 5 away from the work. When the roll 26' on the upper end of the lever 26 rides up the slope C—D of the cam and 70 75 on to the lobe D—A, the arm 32 will be raised

until it strikes the adjustable stop 34. The parts remain in this position until the cam 25 has revolved far enough to allow the roll to start down the slope A—B. At this time the spring 33 acts through the arm 32 to rotate the quill 5 in a clockwise direction, the rate of this rotation, however, being controlled continuously by the contour of the cam. This control is effective by virtue of the fact that a solid, substantially non-compressible column of liquid continuously connects the pistons 28 and 30. During this clockwise rotation of the quill, the grinding wheel 5 is moved toward the work, this motion being rapid during the interval A—B and more gradual as the roll follows the slope B—C. At some 15 point in this slope the wheel comes in contact with the work, the grinding operation is begun, and it is completed during the dwell which occurs after the projection 38 on the quill has come into contact with the stop 37 on the wheel 20 head. The cycle then has been completed, and the parts are ready for a repetition of this cycle.

A very important feature of this invention resides in the adjustment whereby any desired portion of the slope B—C of the cam can be used 25 to control the approaching and wheel feeding movement. That is, this movement can be terminated at any point in the slope B—C, and the remainder of said slope can be utilized for the dwell period. Thus the slope B—C can be functionally divided, as above indicated. This result is effected by the adjustment of the stop 34. The manner in which it is produced will be best understood by first describing the hydraulic system 30 connected with the power transmitting column 35 29.

Referring more especially to Fig. 4, it will be seen that the hydraulic system there illustrated includes a pump 13 which may be driven as illustrated in Fig. 1, and which draws oil from the tank 14 and forces it through a pipe 16 in which a relatively low pressure is maintained by the automatic relief valve 19 through which a stream of oil is always flowing. This pressure must be sufficient to move the pistons 28 and 45 30, but unable to overcome the resistance of the spring 33. Oil from the pipe 16 can pass through the check valve 21 into the transmitting column in the pipe 28 when the pressure in this column is lower than that in the pipe 16. 50

It should also be observed that, assuming the stop 34 to be so adjusted that it just permits the complete transmission of the entire movement produced by the lobe C—D, any downward adjustment of the stop will result in preventing the full transmission of the movement of the piston 28 to the piston 30. In other words, the piston 30 will force the arm 32 against the stop 34 at some point in the slope C—D of the cam. The excessive pressure created in the hydraulic 60 column by the continued movement of the piston 28 after the piston 30 has been stopped, will be relieved by the escape of oil through the automatic relief valve 22, this valve being set to hold a pressure considerably higher than the 65 valve 19, but to relieve the pressure before any parts would be unduly stressed. Under such conditions, and upon the return movement of the quill produced by the spring 33, the rotation of the quill will be interrupted by the stops 37 and 70 75 38 while the roll 26' is on some part of the slope B—C, the exact point on this slope being determined by the adjustment of the stop 34. A further rotation of the cam after this point has been reached would, if other conditions permit. 75

ted, reduce the hydraulic pressure in the pipe 29 to zero, and during the rest of this rotation, until the roll starts up the slope C—D, the pistons 28 and 30 would be left in a free or floating condition, there being no tendency to move them in either direction.

Thus any desired portion of the slope B—C of the cam can be utilized in controlling the approach of the wheel to the work and its feeding movement at a predetermined speed after the grinding operation has been initiated.

The interval of abnormally low pressure just described is utilized to introduce new fluid into the system to replace any loss that has occurred during the cycle due to the escape of liquid through the pressure relief valve 22 because of excessive pressures created. As above stated, oil under low pressure is maintained continuously flowing through the pipe 16. Consequently, as soon as the hydrostatic pressure in the pipe 29 falls below that in the pipe 16, oil will flow automatically through the check valve 21 into the pipe 29, this flow continuing until the pipe is completely filled, the piston 30 has been forced outwardly as far as it is permitted to go by the arm 32, and the piston 28 has been moved outwardly as far as the cam 25 will permit.

As above pointed out, leakage is an unavoidable factor in a mechanism of this type, and while the amount of liquid lost in each cycle is very small, if this loss is allowed to accumulate it will introduce serious errors in subsequent cycles, and eventually will make the transmitting mechanism inoperative. However, the arrangement above described for replenishing the loss of liquid which escapes through the pressure relief valve, also operates automatically to replace any liquid lost by leakage. In other words, the power transmitting portion of the system is automatically filled with oil at the end of each cycle and before the next cycle is commenced, so that there can be no accumulation of lost motion due to leakage from any cause.

Such an hydraulic system as that shown may also be used in connection with the hydraulic operation of other elements of the system, and it is contemplated that the invention may be applied to machines equipped with a hydraulic system used to perform other functions. Such an embodiment of the invention is illustrated diagrammatically in Fig. 5. Here the supply tank 14, pump 13, and pipe 16 are arranged as above described, but the pipe 16 is connected to a valve 40, located in a valve casing 41, and the valve is operated by a cam 39, mounted on the cam shaft 24, which also carries the cam 25 previously referred to. The valve mechanism 40—41 and its operating cam constitute a control mechanism for operating a piston 44 which may be made to move any load, indicated diagrammatically at 45. The pressure relief valve 17 maintains the pressure in the supply pipe 16 necessary for operating the piston 44.

In this arrangement the oil exhausted from the cylinder in which the piston 44 works and from the valve cylinder 41 is returned through pipes 18a and 18b, and a branch pipe 18c runs from the pipe 18a to the check valve 21, thus conducting oil to the pipe 29 which connects the cylinders 35 and 36 of the construction shown in Figs. 1 and 4. A pressure relief valve 22 also is connected into this system to function as in the arrangement previously described. In order to maintain in this system a pressure sufficient to move the pistons 28 and 30, as previously de-

scribed, while still limiting this pressure to the requirements of the spring 33, a pressure relief valve 19 is connected to the discharge end of the pipe 18a and is itself connected through the pipe 20 with the tank 14. This valve is so adjusted that it maintains the desired pressure on the system 18a, 18b, 18c and 29, such pressure being predetermined and varied to suit the requirements of individual cases by adjustment of the valve 19. Thus this hydraulic system can be made to serve several purposes. The system illustrated diagrammatically in Fig. 5 is shown also in Fig. 1, only those parts of the system necessary to an understanding of the operation of Fig. 1 being illustrated, however, in the latter figure.

Instead of using the power stroke of the piston 28 to move the wheel 5 outwardly, as in the constructions above described, and utilizing a spring to produce the inward movement of the wheel, these operations may be reversed. In some situations such a reversal is desirable in order to avoid alterations of the feeding movement which might be necessary if the arm 32 of the quill 46 remained against the stop 34 for an excessively long time. It is also contemplated that if a large retraction of the wheel is desired, or when other special conditions make it advantageous, the piston 28 may be replaced by a plurality of pistons, one of which will operate to produce the slow motion of the wheel, and another to effect its quick retracting movement. Such a construction is illustrated in Fig. 6. Here the spring 33 rotates the quill 46 in a direction to move the grinding wheel away from the work, this movement being limited by the stop 34, while the piston 30 produces the opposite rotation of the quill. Also, the piston 28 has been replaced by two pistons, designated at 49 and 50, respectively, both connected with the piston 30 through the pipe 29, and cams 47 and 48 secured to the cam shaft 24 are provided to operate the respective pistons 49 and 50. In other respects the construction shown in Fig. 6 is essentially like that illustrated in Fig. 5. The cam 47, Figs. 6, 7, and 8, controls the quick retracting movement of the wheel, while the cam 48, Figs. 6, 9, and 10, controls the slow motion of the wheel. In this arrangement the piston which produces the outward movement may conveniently be of large diameter, thus permitting a cam of small rise to produce a relatively large retracting movement of the wheel, while that which controls the slow motion can be of smaller diameter so that long slow motion surfaces of the cam may be utilized, and thus the effect of slight inaccuracies in the surface of the cam will be minimized.

In order to cushion the shock which otherwise would be caused by the sudden stopping of the piston 44, Fig. 6, at each end of its stroke, the two pipes 42 and 43, which conduct liquid to and from the cylinder in which this piston works, may be connected closely adjacent to the cylinder by pipes 61 and 62, respectively, and pressure relief valves may be connected in to these two pipes so that the flow permitted through one pipe will be opposite to that through the other. These valves should be set to open at pressures slightly higher than the operating pressures in the pipes 42 and 43. The valve 40 customarily is timed to close either port which momentarily serves as the exhaust, an instant before the piston reaches the end of its stroke, and the high pressure set up by the momentum of the piston and the parts moving with it thus is exerted on the oil trapped in the pipe which,

immediately prior to this instant, has been conducting the exhaust oil. With the arrangement shown, the high pressure so created can be relieved through one or the other of the pipes 5 61 and 62 by the opening of its pressure relief valve, but the valve can be adjusted so that it will give the desired cushioning action to the piston and bring it to a stop before it reaches the end of its stroke.

10 It will be observed that the motions of the cam 25 which are transmitted to the quill 46 can be modified by making suitable changes in the ratio of the arms of the lever 26, or in the ratio of the areas of the pistons 28 and 30.

15 In addition, the lever 26 may be made adjustable to increase or decrease the basic motion of the cam 25 which is utilized in operating the parts driven therefrom. Such an arrangement is illustrated in Fig. 11 in which the general 20 machine organization shown is essentially like that illustrated in Fig. 1, but the cam shaft 24 and cam 25 have been moved into a different location. Also the cylinder 35, in which the piston 28 works, is located horizontally. Instead of the 25 lever 26, a compound lever mechanism is utilized to transmit motion from the cam 25 to the piston. This mechanism comprises a lever 52 having a roll 53 mounted in its free end and running on the surface of the cam 25. Another 30 lever 54, extending in a generally parallel relationship to the lever 52, bears against the end of the piston rod. The movement of the lever 52 is transmitted to the lever 54 by means of a roll 55, mounted in a block or holder 56, which 35 slides in a dove-tail guideway formed in the lever 52. Bolts 57, extending through a long slot in the lever 52, are threaded into the block 56 and serve to hold it in any position of adjustment.

40 It will be clear from an inspection of Fig. 11 that adjustment of the block 56 downwardly toward the cam will increase the movement imparted to the piston 28 by a given throw of the cam, while adjustment of the block 56 upwardly 45 will decrease said movement. Thus the basic motion of the cam 25 can be increased or decreased through appropriate adjustments of this compound lever mechanism.

Initial adjustment of the entire wheel head 50 may be made manually toward and from the work by means of the hand wheel 7. Since this adjustment involves a movement of translation of the cylinder 36 relatively to the frame 1, some provision for it must be made in the pipe or 55 hydraulic transmitting column 29. This may consist in introducing a flexible section 60, Fig. 11, in the pipe 29. Or, swivel jointed rigid sections of pipe may be included in these connections between the cylinders 35 and 36 to accomplish 60 the same object. In either event the sections should not be of variable volume.

The invention thus provides a fluid actuated transmitting mechanism for use in automatic grinding machines and other machine tools which 65 is relatively simple in construction, can be manufactured economically, is readily adaptable to a great variety of designs, while avoiding the complications and limitations which necessarily are involved in producing the same operations 70 mechanically, and which, in addition, is flexible in operation and extremely accurate.

While in the machine above described the reciprocating movement of the wheel 5 toward and from the work occurs in the arc of a circle 75 around the center of the quill, it is obvious that

the invention is equally applicable to the production of a straight line reciprocating movement of the wheel, or of any suitable movement of the wheel head to carry the wheel toward and from the work. Likewise, this mechanism is useful in 5 producing an axial reciprocating movement of the wheel as for example, in grinding to a shoulder.

While I have herein shown and described typical embodiments of my invention, it will be 10 understood that the invention may be embodied in a great variety of forms without departing from the spirit or scope thereof. For example, while I have shown pistons working in cylinders to produce the hydraulic transmission of 15 the movements desired, it is obvious that these devices could be replaced by bellows, diaphragms, vanes, or the like, where desirable, the latter elements being equivalents of the former.

Having thus described my invention, what I 20 desire to claim as new is:

1. In a grinding machine, the combination of a grinding wheel, means supporting said wheel for reciprocating movement toward and from the work, a power driven cam, a piston operated by 25 said cam, a second piston, cylinders for said pistons, means confining a column of liquid connecting said cylinders and operative to hydraulically transmit motion from one of said pistons to the other, means connecting said second piston with said wheel to cause the latter piston to move the wheel relatively to the work, liquid supplying means connected with said column and including a pump and a liquid supply line leading from said pump to said column, a check valve in 30 said line permitting liquid to flow into the column, and means for automatically maintaining pressure in 35 said supply line sufficient for operating purposes.

2. In a grinding machine, the combination of a 40 grinding wheel, means supporting said wheel for reciprocating movement toward and from the work, a power driven cam, a piston operated by said cam, a second piston, cylinders for said pistons, means confining a column of liquid connecting said cylinders and operative to hydraulically transmit motion from one of said pistons to the other, means connecting said second piston with said wheel to cause the latter piston to move the wheel in one direction relatively to the work, 45 a spring connected with said wheel to move it in the opposite direction when permitted to do so by said second piston and its connections with said cam, liquid supplying means connected with said column and including a pump and a liquid supply line leading from said pump to said column, a check valve in said line permitting liquid to flow into the column, and means for automatically maintaining pressure in said supply line sufficient for operating purposes and of such 55 a value that said spring can return said second piston against said pressure but only as said cam permits such return.

3. In a grinding machine, the combination of a 60 grinding wheel, means supporting said wheel for reciprocating movement toward and from the work, a power driven cam, a piston operated by 65 said cam, a second piston, cylinders for said pistons, means confining a column of liquid connecting said cylinders and operative to hydraulically transmit motion from one of said pistons to the other, means connecting said second piston with said wheel to cause the latter piston to move the wheel in one direction relatively to the work, 70 a spring connected with said wheel to move it in 75

the opposite direction when permitted to do so by said second piston and its connections with said cam, liquid supplying means connected with said column and including a pump and a liquid supply line leading from said pump to said column, means for limiting the pressure maintained in said supply line to a substantially predetermined value, a check valve in said line permitting liquid to flow into the column, and a pressure relief valve connected with said column and limiting the pressure created therein.

4. In a grinding machine, the combination of a machine frame, a bed mounted on said frame, a pivotal connection between said bed and said frame whereby the bed may be adjusted angularly about said connection relatively to the frame, a grinding wheel mounted on said bed for reciprocation toward and from the work, a power driven cam, a piston operated by said cam, a second piston, cylinders for said pistons, means connecting said second piston with said wheel to cause the latter piston to move the wheel, and means confining a column of liquid extending through said pivotal connection and connecting said cylinders for hydraulically transmitting motion from said first piston to said second piston.

5. In a grinding machine, the combination with a grinding wheel, a shaft supporting said wheel, a rotary quill in which said shaft is mounted eccentrically, an arm rigid with said quill and extending laterally therefrom, a power driven cam, a piston operated by said cam, a second piston, cylinders for said pistons, means confining a column of liquid connecting said cylinders and operative to transmit the motion of said first piston to said second piston, and means connecting said second piston with said arm to cause the movement of the latter piston to rock said quill in one direction.

40 6. In a grinding machine, the combination with a grinding wheel, a shaft supporting said wheel, a rotary quill in which said shaft is mounted eccentrically, an arm rigid with said quill and extending laterally therefrom, a power driven cam, a piston operated by said cam, a second piston, cylinders for said pistons, means confining a column of liquid connecting said cylinders and operative to transmit the motion of said first piston to said second piston, means connecting said second piston with said arm to cause the movement of the latter piston to rock said quill, and means for automatically maintaining the same basic volume of liquid in said hydraulic transmission column during the movement of said wheel by said second piston in successive cycles of operation of the machine.

7. In a grinding machine, the combination with

a grinding wheel, a shaft supporting said wheel, a rotary quill in which said shaft is mounted eccentrically, an arm rigid with said quill and extending laterally therefrom, a power driven cam, a piston operated by said cam, a second piston, cylinders for said pistons, means confining a column of liquid connecting said cylinders and operative to transmit the motion of said first piston to said second piston, means connecting said second piston with said arm to cause the movement of the latter piston to rock said quill in one direction, a stop for limiting the movement so transmitted to said arm, a spring connected with said arm to move it in the opposite direction, and a second stop for limiting the movement of the arm produced by said spring, one of said stops being adjustable.

8. A grinding machine according to preceding claim 7, including a liquid supplying means comprising a pump and a supply line leading from said pump to said column, a check valve in said supply line permitting the free flow of fluid therefrom into said column, a pressure relief valve connected with said column, and means cooperating with said pump to maintain a minimum operating pressure in said column and for limiting said pressure to a value below that applied to the system by the action of said spring on said second piston.

9. A grinding machine according to preceding claim 3, including a second hydraulically actuated unit to which liquid is supplied by said pump, power driven means positively connected with said shaft for controlling the operation of said second unit, and means for maintaining the normal operating liquid pressure for said second unit at a different value from that in said hydraulic transmitting column.

10. In a grinding machine, the combination of a grinding wheel, means supporting said wheel for reciprocating movement toward and from the work, two power driven cams, independent pistons operated by said respective cams, a third piston, cylinders for said pistons, means confining a column of liquid connecting the cylinders for the first two pistons with that for said third piston to hydraulically transmit motion from the first two pistons to the third piston, means connecting said third piston with said wheel to move the wheel relatively to the work, and means for automatically maintaining the same basic volume of liquid in said hydraulic transmission column during the movement of said wheel by said third piston in successive cycles of operation of the machine.

HARRY ARTER.
